175,125

CORNER SHELF OR SIMILAR ARTICLE

William V. McNamara, Boston, Mass.

Application March 8, 1955, Serial No. 34,952

Term of patent 7 years

(Cl. D33—1)

Fig. 1.

Fig. 2.

Fig. 3.

Fig. 4.

I claim:

The ornamental design for a corner shelf or similar article, substantially as shown.
